UNITED STATES PATENT OFFICE

112,151

DESIGN FOR AN ICE CREAM DIPPER

Robert J. Price, Uniontown, Pa.

Application May 11, 1938, Serial No. 77,120

Term of patent 14 years

To all whom it may concern:

Be it known that I, Robert J. Price, a citizen of the United States, residing at Uniontown, in the county of Fayette and State of Pennsylvania, have invented a new, original, and ornamental Design for an Ice Cream Dipper, of which the following is a specification, reference being had to the accompanying drawing, forming part thereof.

In the drawing:

Fig. 1 is a view of the ice cream dipper in side elevation, the outer portions of the handles being broken away;

Fig. 2 is a front view of Fig. 1 in elevation;

Fig. 3 is a plan view of the dipper in open position;

Fig. 4 is a plan view, partly in section on the line IV—IV of Fig. 1.

I claim:

The ornamental design for an ice cream dipper, as shown.

ROBERT J. PRICE.
